APPARATUS FOR HOLDING INFANTS

Pearl M. Rogatz, Milwaukee, Wis.

Application March 13, 1948, Serial No. 14,791

3 Claims. (Cl. 155—45)

1

This invention relates to nursery apparatus useful in handling infants, especially while bathing them.

The bathing of infants too large to occupy the customary baby bath, generally formed of canvas or similar fabric and sold on the market under the trade name "Bathinette," invariably presents a problem. The child is too small to be trusted to sit erect in an ordinary bathtub and consequently he must be held.

With a view toward overcoming this objection devices have been proposed in the past in the nature of seats adapted to be fastened or otherwise positioned in a bathtub, and which were intended to hold the infant in a seated posture. These devices, however, are not too satisfactory as they do not permit the necessary freedom of movement.

It is an object of this invention, therefore, to provide a nursery apparatus especially adapted for use in the bathing of infants but which is equally useful in dressing them and also can be used as a cradle or bed if desired.

More specifically it is an object of this invention to provide a device adapted to be set into a bathtub and in the form of a reclining lounge on which a child may be supported in a reclining position.

Another object of this invention resides in the provision of a nursery device in the form of a reclining lounge on which the child may be supported in a reclining position and having a portion of its supporting surface detachable at one end of the lounge to enable the infant to occupy a seated position on the device.

Still another object of this invention resides in the provision of a device adapted to support an infant either in a reclining or seated position and which embodies a framework of tubular construction having spaced opposite side rails between which a fabric panel is stretched, with an offset portion medially of the side rails holding the fabric panel in the form of a seat.

Still another object of this invention resides in the provision of a device of the character described with a safety harness which is attached to the fabric panel of the device and adapted to pass around the waist of an infant supported on the panel to hold the infant on the device while allowing him limited freedom of motion.

With the above and other objects in view, which will appear as the description proceeds, this invention resides in the novel construction, combination and arrangement of parts substantially as hereinafter described and more particularly de-

2

fined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

10 Figure 1 is a perspective view of the nursery device of this invention indicating in construction lines the manner in which an infant is supported thereon in a reclining position;

15 Figure 2 is also a perspective view but illustrating a portion of the fabric panel at the lower end of the device detached from its supporting rails and indicating in construction lines the manner in which an infant is supported on the device in a seated position;

20 Figure 3 is a side elevational view of the device; Figure 4 is a cross sectional view taken through Figure 3 on the plane of the line 4—4;

25 Figure 5 is an end elevational view of the device viewing the same from the low end thereof;

Figure 6 is a plan view of the device illustrated in Figures 3 and 5;

Figure 7 is a plan view of the panel per se prior to attachment thereof to the framework of the device; and

30 Figure 8 is an enlarged detail perspective view illustrating the manner in which the leg structure for the low end of the frame is attached to the side rails of the frame.

Referring now more particularly to the accompanying drawings in which like numerals indicate like parts, the numeral 10 generally designates the nursery device of this invention. It comprises a fabric panel 11 stretched between and secured to the opposite side rails 12 of a framework 13 of tubular construction. For strength and also for sanitary reasons the framework 13 is made up of metal tubes having a bright chromium finish which is easily kept clean.

The side rails 12 are bent downwardly as at 45 14 at opposite ends thereof and have leg structures 15 and 16 connected thereto at the front and rear ends of the frame respectively.

The leg structure 15 for the front end of the frame comprises a tubular member having a cross piece 17 of a length to substantially define the width of the frame, and upright extensions 18 bent up from the opposite ends of the cross piece give the front leg structure a substantial U-shape.

The front leg structure is attached to the frame 55 by screws 20 passing through diametrically op-

posite holes 21 in the ends of each leg 14 and extension 18 and threading into tapped holes 22 in a nipple 23, part of which is received in the open end of the leg 14 and the other part of which is received in the open end of the extension 18. The spacing of the holes 21 and 22 is such that the extremities of the legs 14 and the extensions 18 abut one another as shown in Figures 2 and 3 and thereby lend rigidity to the joint between the front leg structure 15 and the frame.

At the rear of the frame the downwardly bent legs 14 of the side rails have laterally bent extensions 25 thereon crossing one another and hence extending to opposite sides of the frame. The extensions are rigidly joined together at the point where they cross one another, as by welding 26. Downwardly projecting vertical portions 27 on the outer ends of these crossing leg extensions have rubber pads 28 fixed on their extremities and these pads may be in the nature of suction cups. Similar pads or suction cups 29 secured to the underside of the cross piece 17 on the front leg structure enable the framework to be inserted in a bathtub or placed upon any supporting surface without danger of slippage or tilting of the frame.

It will be noted that the front leg structure 15 has relatively little height so that the front of the framework is relatively low. The leg structure 16 at the rear of the frame, however, has greater height so as to hold the rear of the frame at a substantial elevation with the side rails 12 parallel but inclined to horizontal.

Medially of their ends the side rails are bent to provide relatively short offset portions 30 which lead downwardly and rearwardly in an oppositely inclined direction, and the offset thus produced in the fabric panel 11 stretched between the side rails provides a seat 31 which is adapted to support an infant in a seated position on the device.

The fabric panel 11 may be a length of canvas or other fabric having substantial strength, and it is preferably rubberized or otherwise treated to have water repellent characteristics. As best seen in Figure 7 the panel 11 is comprised of two sections, a front section 33 and a rear section 34 integral therewith but defined therefrom by notches 35 cut into opposite side edges of the panel near its medial portion but ahead of the seat 31 thereof.

The panel has sufficient length as to extend beyond the opposite ends of the side rails and sufficient width as to allow marginal flap portions 36 at the opposite sides of the panel section 34 to be folded around the side rail portions rearwardly of the seat 31 so that when stitched onto the underside of the panel as at 37 the flaps 36 securely hold the rear section of the panel in place on the device.

The rear section 34 of the panel has sufficient length to enable its rear end to be folded over the rear of the frame as seen in Figures 1, 2, and 3 with the side flaps 36 covering the downwardly bent leg portions 14 at the rear of the side rails.

The front panel section 33 likewise has marginal flaps 39 at its opposite side edges which are adapted to pass around the lengths of the side rails forwardly of the seat 31 including the downwardly bent ends 14 at the front of the frame. These flaps, however, have snap fasteners 40 fixed thereto for cooperation with mating fasteners 41 on the body of the flap to enable the section 33 to be detached from the front portion of the frame.

With the panel entirely secured to the framework as illustrated in Figure 1, the device is adapted to support an infant in a reclining position as indicated, but when the snap fasteners holding the opposite sides of the front panel section 33 to the side rails are disengaged, the front section 33 of the panel is freed from the side rails and may be folded rearwardly under the seat 31 as shown in Figure 2 to allow an infant to occupy a seated position upon the device.

An infant is adapted to be securely held upon the panel either in a reclining or seated position by means of a safety harness generally designated 42. This harness comprises a longitudinal strap 43 the medial portion of which is stitched to the seat 31 of the panel as at 44, so that the opposite ends of the strap extend towards the opposite ends of the framework. A belt-forming strap 45 has its medial portion stitched as at 45' to one end of the strap 43, preferably the rear end, and the belt-forming strap has a length such that it may pass entirely about the waist of an infant supported on the panel. In addition the belt-forming strap 45 is provided with a plurality of snap fasteners 46 at each end thereof for cooperation with mating fasteners 46 fixed to the opposite end of the strap 43 to enable securement of the strap 45 about the waist of an infant.

In use the infant is placed upon the panel 11 with its lower body portion directly over the seat 31 of the panel and upon the rear end of the strap 43 so that the front end of this strap may be brought up between the legs of the infant and secured to the opposite ends of the belt-forming strap 45 passed around the infant's waist. It is important to note that there are sufficient fasteners 46 to allow a degree of adjustment of the belt-forming strap 45 about the waist of the infant, as it is essential that the harness fit rather snug for the most efficient performance of its function.

It should also be observed that the securement of the strap 43 to the seat 31 of the panel at the mid-portion of the strap renders the harness 42 operative both when the infant is occupying a reclining position and when occupying a seated position.

In order to afford maximum safety, the belt-forming member 45 has relatively short strips of fabric 50 secured thereto at either side of the adjacent end of the strap 43, and the outer ends of the strips 50 are permanently attached to the body section 34 of the panel as by stitching 51. The strips 50 therefore allow an infant in the harness 42 a limited degree of freedom while positively precluding any danger of the infant toppling either sideways or forwardly from the seat portion 31.

From the foregoing description taken in connection with the accompanying drawings, it will be readily apparent to those skilled in the art that the nursery device of this invention features simplicity of construction and consequently low cost, and that it greatly facilitates the handling of infants during bathing and/or dressing since its portability enables it to be placed in a convenient position of use on a table or the like or placed directly in an ordinary bathtub for bathing of the infant. Another highly important feature resides in the fact that the fabric panel is readily removable for laundering, or replacement, merely upon detachment of the front leg structure from the device.

What I claim as my invention is:

1. In a device of the character described: an

elongated frame comprising spaced side rails bent at the ends thereof to form front and rear legs; a removable cross member connecting the legs at one end of the frame; the legs at one end of the frame being longer than those at the other end so as to give the frame a downward tilt; a medial vertical offset in each of the side rails; a fabric panel supported by said side rails and extending therebetween substantially from end to end of the frame; means connecting that portion of the fabric panel which extends from the upper end of the frame down to and including the offset portions of its side rails to the side rails in a manner allowing detachment of the fabric panel upon removal of said cross member by sliding the same along the length of the side rails; and means for readily detachably connecting the lowermost portion of the fabric to the side rails to provide a support for the legs of an infant reclining on the device, and so that upon detachment from said lowermost portion of the fabric from the side rails an infant may occupy a seated position on the device with its feet between the side rails.

2. In a device of the character described: a frame including a pair of spaced apart side rails and a leg structure at each end of the frame to hold the side rails inclined downwardly and forwardly with respect to the horizontal, each of said rails being bent medially of its ends to provide a relatively short upwardly and rearwardly inclined offset portion; a fabric panel having a length at least equal to that of said rails and having each of its side edges, from a medial point to one end thereof, secured to the medial and upper portions of one of the side rails, the section of the panel supported from the medial portions of the side rails being adapted to provide a seat for an infant having its legs between the lower portions of the side rails and the section of the panel supported by the upper portion

of the side rails being adapted to provide a back rest for an infant in a reclining position; means for readily detachably connecting the side edges of the remaining section of the fabric panel to the lower portions of said side rails when it is desired to provide a support for the extended legs of an infant reclining on the panel; and a substantially T-shaped safety belt having the medial portion of its stem member permanently secured 10 along the longitudinal center of the seat section of said panel and having readily detachable connecting means at its free ends to enable the same to be connected together, with the stem portion of the T passing between the legs of the infant and the arms thereof embracing the waist of an infant to hold the infant on the device in either a seated or a reclining position.

3. The device of claim 2 further characterized by the provision of a pair of connecting strips each having one of its ends secured to an arm of the belt and its other end secured to the seat section of the panel adjacent to one of said side rails, said sections preventing an infant in said belt from toppling either sidewise or forwardly 20 off the device.
